COMBINED FOOD GRATER AND BOWL

Harold P. Ashton, Providence, and James B. Swett, Barrington, R.I., assignors to Dart Industries Inc., Los Angeles, Calif.

Filed Dec. 30, 1970, Ser. No. 26,704

Term of patent 14 years

Int. Cl. D7—04

U.S. Cl. D89—1

FIG. 1

FIG.2

FIG.3

FIG. 4

FIG. 5

FIG. 6

FIG. 7

FIG. 8

FIG. 1 is an exploded top perspective view of a combined food grater and bowl showing our new design;

FIG. 2 is a top perspective view thereof in an assembled condition;

FIG. 3 is a top perspective view thereof, the greater being inverted;

FIG. 4 is a bottom plan view thereof;

FIG. 5 is a front elevational view of FIG. 2;

FIG. 6 is a side elevational view as seen from the right of FIG. 2;

FIG. 7 is a front elevational view of FIG. 3; and

FIG. 8 is a side elevational view of FIG. 3.

We claim:

The ornamental design for a combined food grater and bowl, substantially as shown.
